UNITED STATES PATENT OFFICE.

FREDERICK C. HANSON, OF OMAHA, NEBRASKA.

WATER-SOFTENING APPARATUS.

1,035,436.

Specification of Letters Patent. Patented Aug. 13, 1912.

Application filed December 13, 1911. Serial No. 665,539.

To all whom it may concern:

Be it known that I, FREDERICK C. HANSON, a citizen of the United States, residing at Omaha, in the county of Douglas and State of Nebraska, have invented certain new and useful Improvements in Water-Softening Apparatus, of which the following is a specification.

This invention relates to an improved water-softening apparatus of the class employing the force of gravity for automatically moving the mechanical parts to effect the mixing of a liquid chemical or softening agent, in measured quantities, with a supply of water, and generally used in connection with laundries.

One of the objects of the invention is to provide a water softening apparatus which may be used in the treatment of either hot or cold water, so constructed and arranged that the liquid softening agent will be conducted to the discharge pipes of the water measuring receptacles or compartments and will be discharged into and caused to flow with the discharged water to thereby become thoroughly mixed with the water which is treated.

Another object is to provide means which will cause a distribution of the softening agent uniformly with and in exact measured quantities to the water to be treated.

The invention also includes a new means whereby the liquid softening agent may be agitated to advantage; means for opening the valves of the measuring receptacles coincidently with the flow of the liquid softening agent, and adjustable devices for increasing or decreasing the supply, as may be desired, of the softening agent.

With these objects in view, and others to be hereinafter mentioned, the invention presents a novel construction, combination and arrangement, as described herein and claimed, and as illustrated in the drawing, it being understood that changes in form, size, proportion and minor details may be made within the scope of the claims without departing from the spirit of the invention, or sacrificing any of its advantages.

In the accompanying drawing, Figure 1 is a plan view of a water softening apparatus embodying my invention. Figs. 2 and 3 are detail views relating to the containers for elevating the chemical solution, Fig. 2 being a side view of the container, the upright guide and pocket being broken away;

Fig. 3 showing the container in longitudinal section, as on line *a a* of Fig. 2. Fig. 4 is a vertical section of the casing on line *b b* of Fig. 1, to show the arrangement of valves 60 in the bottoms of the water-measuring receptacles. Fig. 5 is a detail, being a plan view showing the agitating frame upon the bottom of the solution tank. Fig. 6 is a vertical section on line *c c* of Fig. 1, to show 65 the actuating buckets and levers connected therewith. Fig. 7 is a vertical section on line *d d* of Fig. 1, showing the slidably mounted containers for elevating the chemical solution. Fig. 8 is a vertical front view 70 of the casing showing a weighted arm and toothed segment mounted upon the actuating shaft for preventing movements of the actuating buckets, when empty.

Referring now to the drawing for a more 75 particular description, numeral 9 indicates a casing, preferably rectangular in form; and in the casing, parallel with its front and rear walls 10 and 11, are provided upright partitions 12 and 13. Between the rear wall 80 11 and partition 13 is provided a flat bottom 14 (Fig. 4.), and midway between the sides of the casing to connect with wall 11 and partition 13 is provided the upright cross partition 15, whereby two compartments of 85 equal size and adapted to contain water are formed, and for convenience they are designated as measuring receptacles or compartments 16 and 17. A bottom 18 (Fig. 7.) is provided between the front wall 10, partition 12 and the side walls of the casing to 90 form a tank 19, for containing a chemical solution.

At the top and near the front part of the casing and disposed parallel with partition 95 12 is indicated a supporting strip 20 having, midway between the side walls 21 of the casing, a downwardly projecting bracket 22, best shown in Fig. 7.

At 23, disposed midway between the side 100 walls and near the upper part of the casing, is indicated a horizontal operating shaft, said shaft traversing partitions 12 and 13, and having suitable bearings at its respective ends in bracket 22 and upon the rear 105 wall of the casing. Rigidly mounted upon shaft 23 to overhang receptacles 16 and 17 is a flat deflecting plate or trough 24.

At 25, above shaft 23 (Fig. 4.), is indicated a water supply pipe, and it will be 110 understood that a partial rotation of this shaft in one direction would dispose the

trough inclinedly, and when inclined as illustrated in said Fig. 4, water coming from supply pipe 25 would flow into receptacle 16. And if shaft 23 has a part rotation in the opposite direction, trough 24 would be inclined in a manner to cause the water from the supply pipe to flow into receptacle 17. Receptacles 16 and 17 are each provided, in their bottom with a valve 26 and a discharge pipe 27, and water from these receptacles may be discharged through pipes 27 into a receiving tank or other container disposed immediately below casing 9 (not shown).

15 At 28 above valves 26, is indicated a rock lever; it is loosely mounted upon shaft 23 and is provided near its ends with upwardly projecting spiral springs 29; upright links 30 extend between and are pivotally mounted at their terminals upon the valve caps and the ends of this rock lever. Rigidly mounted upon shaft 23 and disposed above rock lever 28 is rock-bar 31 adapted to bear upon springs 29, and it will be understood that if shaft 23 is partly rotated in either direction it will result in the longitudinal movements of links 30 in directions opposed to each other, and thereby one of valves 26 will be opened and the other will be closed, the operation being that the ends of rock-bar 31, during its swinging movements will actuate springs 29 in alternation, to effect corresponding movements of the rock lever and movements of the links connected therewith.

From the description it will be seen that when valve 26 of one of receptacles 16 or 17 is closed, trough 24 at that time will be inclined in a manner to cause the water from supply pipe 25 to pass therein, and water within the opposite receptacle may, at that time, be discharged through the opposite valve. While springs 29 could perhaps be dispensed with, their use is a great advantage for causing a complete closure of the valves when links 30 move downward.

Means are provided and will now be described for causing a part rotation, in opposite directions, of shaft 23, as above mentioned. Casing 9 is formed with an open bottom 32, between partitions 12 and 13. At 33 is indicated an actuating shaft, disposed parallel with and below shaft 23; said shaft may have any suitable bearings, but preferably it traverses partition 12 and wall 10 of the casing, and has terminal bearings upon wall 10 and partition 3. Suitably spaced apart and rigidly mounted, midway between their ends, upon shaft 33 is a pair of rock-arms 34 (Fig. 6), each having at its middle an upwardly projecting, transverse finger or lever 35, and disposed between the respective ends of rock-arms 34 are actuating buckets 36 and 37, said buckets having, at substantially the middle of their end walls,

a pivotal mounting 38 upon the ends of said rock-arms. At 39, rigidly mounted at its middle upon shaft 23, is indicated a rock-bar having a slotted, rigid, downwardly-projecting finger or lever 40 pivotally connected at 41 with the finger or lever 35. Links 42 are employed, their upper and lower ends being pivotally connected at 43 and 44, respectively, with the ends of rock bar 39 and the lower ends of the actuating buckets. Mounted in and near the upper part of partition 13 and extending above the actuating buckets are water passageways, spouts or troughs *e* leading from receptacles 16 and 17, and the mounting provided for the actuating buckets is such that at the time one of said buckets is disposed in an upright position, the opposite bucket will be inclined.

During operation, if the valve in receptacle 16 is closed and the water from pipe 25 is flowing, the water will flow from the spout *e* of this receptacle within bucket 36, after said receptacle has been filled, and on account of the weight of this bucket and its contents, it will swing downward to cause a part rotation of shaft 33. This movement of shaft 33 will cause a closure of the valve of receptacle 17 and the inclination of trough 24 will be changed in a manner to cause the water from pipe 25 to be discharged into the last named receptacle, and the valve of receptacle 16 will be opened, since links 42 are connected with the bottoms of the respective buckets and with the rock lever 39. At this time shafts 23 and 33 have their part rotations in opposite directions, and the levers or fingers 35 and 40 assist in operation, since they prevent undue vibrations and any lateral play of buckets 36 and 37 during their swinging movements.

Rigidly mounted upon the front end of shaft 23, above tank 19 is rock lever 45 (Fig. 7.). Mounted upon walls 21 and disposed within the tank are containers or pockets 46 and 47; and conducting pipes 48 and 49 extend between and connect these pockets, respectively, with the discharge pipes 27 of receptacles 16 and 17. Within tank 19, adjacent to pockets 46 and 47 are indicated vertical strips or guides 49', their upper ends preferably being mounted upon the walls of the pockets, their lower ends being secured upon the bottom of the tank.

At 50 are indicated comparatively small, tubular containers of uniform diameters, each being provided on its side wall with projections or lugs 51 for the support therebetween of rollers 52; and said containers are mounted in a manner to be moved slidably upon the guides, the walls of the containers being in contact with the inner sides of the guides, and the rollers engaging the opposite or outer sides of said guides.

At 53 are indicated links, handles or bails

for the containers, their lower and upper ends being pivotally mounted, respectively, upon the lower parts at opposite sides of the containers and upon the ends of rock lever 5 45; and it will be understood that the movements of shaft 23, already described, will cause containers 50 to be elevated in alternation, and if tank 19 is filled or provided with a suitable supply of chemical solution it will 10 be deposited in measured quantities in pockets 46 and 47 and will be conducted by pipes 48 and 49 to pipes 27, and will become thoroughly mixed with the water when flowing therewith, in said discharge pipes 27.

15 In operation, at the time one of the pockets receives a charge or supply of the chemical solution, as for instance pocket 47, the valve in receptacle 17 will be open, and the solution will therefore flow in common with the water from that valve. Conducting pipes are provided which have bores of limited diameters, this diameter being such that the time required for the flow of water from a receptacle 16 or 17 and 20 the time required for the flow of a chemical solution from the pocket connected therewith will be equal. Provision is made for a stirring-frame for agitating the chemical solution. The frame consists of upright side 25 strips 54 with numerous cross-strips or blades 55 disposed edgewise and connected therewith. The frame is supported upon the bottom of the tank, and when the frame is moved, the sediment which may adhere to 30 or be deposited upon the bottom of the tank may be removed, and the solution will be agitated. To cause reciprocation of the frame, a lever 56 is rigidly mounted upon shaft 33 to project downwardly for a pivotal mounting upon the terminal of handle or lever 57 of the frame, said lever 57 being pivotally mounted at 58 upon a part of said frame, and during operation the frame will be moved longitudinally at each partial rotation of shaft 33. Outwardly of the front 35 wall 10 of the casing upon the terminal of shaft 33 is rigidly mounted the toothed segment 57', and secured upon said wall below shaft 33 is the supporting plate 58' provided with the stub shaft or pivot 59 (Fig. 8.); and mounted upon pivot 59 is the pinion 60 in engagement with the teeth of the segment and having an arm 61 with a weight 62 removably secured thereon and 40 adjustable longitudinally thereof. Plate 58' is provided with ledges or lugs 63, and secured thereon are resilient bearing members or springs 64. The parts are so constructed and arranged that the weighted arm 61 moves in an arc, substantially, of 180 degrees at each partial rotation of shaft 33.

45 One of the functions of the weighted arm is to cause a difference in the balancing of buckets 36 and 37, since there is a period of 50 time, during operation, while one of these

55 buckets is being filled and the other is being emptied, that their weights are equal; at this time the arm is disposed substantially in a horizontal position and tends to maintain the actuating bucket which is being filled in an upright position, as illustrated in Fig. 1. Since the weight is adjustable longitudinally of the arm, the force required for causing the swinging movement of the arm may be conveniently controlled. Also by reason of the provision of the weighted arm and the momentum thereof, shaft 33 may be driven more positively and with a greater force than it would be driven if simply the weight of one of the 60 filled buckets 36 or 37 is depended upon, and thereby, friction is overcome, and an additional force which is fully under control, is provided for moving the levers, valves and 65 containers 50.

70 For the purpose of determining the quantity of the charges of the liquid chemical, each container 50, preferably is provided with a movable bottom 65 carrying a packing ring 66, as shown in Fig. 3; and by 75 means of a rotatable standard or threaded bolt 67 in engagement with the bottom, the latter may be adjusted so that the container will hold greater or lesser amounts of the 80 solution, as may be desired. Each container, preferably, is partly covered by a 85 cap or hood 68 upon a part of its upper end, opposite to its spout 69, and the bolt 67 may be supported by or mounted in the cap 68.

90 It will be understood that water from the supply pipe 25 continues to flow all of the time, during operation, and while one of receptacles 16 or 17 is being filled the other is being emptied. When one of these receptacles is full, the water continues to flow therein until a sufficient quantity of water passes into an actuating bucket from a spout 95 of the receptacle to cause, by force of gravity, a partial rotation of shaft 33. 100 There will be no movement of a shaft or lever while the water is passing from the supply pipe to the receptacle and from thence to the bucket, as last described, but when the bucket has been filled to an extent sufficient to overcome friction of the shafts and 105 levers and to cause a swinging movement of arm 61, and to overcome suction of one of the valves, the bucket will swing downwardly. The inclination of trough 110 thereupon will be changed and the valve of the filled receptacle will be opened; and at this time the momentum of the weighted arm 61 operates to advantage to cause shafts 115 23 and 33 to fully complete their partial rotatable movements. Receptacles or compartments 16 and 17 operate to accurately 120 measure the quantity of water to be treated by the chemical solution, said solution uniting and becoming thoroughly mixed with 125 130

the water while flowing therewith, after entering discharge pipes 27, from conducting pipes 48 and 49.

Having fully described the several parts 5 and their uses, a further explanation relating to operation is not necessary.

What I claim as my invention and desire to secure by Letters Patent is,—

1. In a water softening apparatus, the 10 combination with an oscillatory shaft, a spout mounted upon said shaft and tilttable therewith, a water supply pipe disposed above said spout, a pair of compartments into which said spout alternately discharges, 15 a rocking lever of T form secured to the oscillatory shaft, a second oscillatory shaft, arms extending from said second oscillatory shaft upon opposite sides thereof, buckets pivotally mounted at the outer ends 20 of said arms, links pivotally connected to the outer portions of the T arms and to the lower inner corners of said buckets, and means for actuating the second oscillatory shaft from the first named oscillatory shaft 25 and in unison therewith.

2. In a water softening apparatus, the 30 combination with an oscillatory shaft, a spout mounted upon said shaft and tilttable therewith, a water supply pipe disposed above said spout, a pair of compartments into which said spout alternately discharges, 35 a rocking lever of T form secured to the oscillatory shaft, a second oscillatory shaft, arms extending from said second oscillatory shaft upon opposite sides thereof, buckets pivotally mounted at the outer ends of said arms, links pivotally connected to the outer portions of the T arms and to the lower inner corners of said buckets, and 40 means for actuating the second oscillatory shaft from the first named oscillatory shaft and in unison therewith, said means comprising an arm extending from the second oscillatory shaft and having a pin and slot 45 connection with the T shaped rocking lever.

3. In a water softening apparatus, the 50 combination with an oscillatory shaft, a spout mounted upon said shaft and tilttable therewith, a water supply pipe disposed above said spout, a pair of compartments into which said spout alternately discharges, 55 a rocking lever of T form secured to the oscillatory shaft, a second oscillatory shaft, arms extending from said second oscillatory shaft upon opposite sides thereof, buckets pivotally mounted at the outer ends of said arms, links pivotally connected to the outer portions of the T arms and to the lower inner corners of said buckets, and means for 60 actuating the second oscillatory shaft from

the first named oscillatory shaft and in unison therewith, said means comprising an arm extending from the second oscillatory shaft and having a pin and slot connection with the T shaped rocking lever, an additional rocking lever upon the first named oscillatory shaft, a compartment above which said rocking lever is located, links pivotally connected to the outer ends of said rocking lever, measuring receptacles secured to the 70 opposite walls of said compartment, guide members secured to said measuring receptacles, measuring containers to which said links are pivotally connected, said guide members having goose neck terminals at 75 their upper ends to cause the containers to be tilted at their upward limit of movement.

4. In a water softening apparatus, the 80 combination with an oscillatory shaft, a spout mounted upon said shaft and tilttable therewith, a water supply pipe disposed above said spout, a pair of compartments into which said spout alternately discharges, a rocking lever of T form secured to the oscillatory shaft, a second oscillatory shaft, arms extending from said second oscillatory shaft upon opposite sides thereof, buckets pivotally mounted at the outer ends of said arms, links pivotally connected to the outer portions of the T arms and to the lower inner corners of said buckets, and means for 85 actuating the second oscillatory shaft from the first named oscillatory shaft and in unison therewith, said means comprising an arm extending from the second oscillatory shaft and having a pin and slot connection with the T shaped rocking lever, an additional rocking lever upon the first named oscillatory shaft, a compartment above 90 which said rocking lever is located, links pivotally connected to the outer ends of said rocking lever, measuring receptacles secured to the opposite walls of said compartment, guide members secured to said measuring receptacles, measuring containers to which 95 said links are pivotally connected, said guide members having goose neck terminals at their upper ends to cause the containers to be tilted at their upward limit of movement, 100 a reciprocatory agitator disposed in the bottom of the last named compartment, and means for actuating said agitator from the first named oscillatory shaft.

In testimony whereof I have affixed my 115 signature in presence of two witnesses.

FREDERICK C. HANSON.
